ENGINE STARTER GEARING

James J. Digby, Elmira, N. Y., assignor to Bendix Aviation Corporation, a corporation of Delaware

Application August 30, 1950, Serial No. 182,335

3 Claims. (Cl. 74—7)

1

The present invention relates to engine starter gearing, and more particularly to that type of starter drive in which a pinion is automatically traversed into and out of mesh with an engine gear.

It is an object of the present invention to provide a novel engine starter drive incorporating a torsional spring connection, which is exceptionally small and compact in comparison with standard types of drive of similar load rating.

It is another object to provide such a device in which the yielding driving connection is telescoped over the traversing connection so as to reduce the overall length of the drive.

It is another object to provide such a device in which the traversing means for the pinion comprises a screw and nut, and the reaction of the screw jack action of the screw and nut is taken by the power shaft upon which the drive is mounted.

Further objects and advantages will be apparent from the following description taken in connection with the accompanying drawing in which—

Fig. 1 is a side elevation partly broken away and in section of a preferred embodiment of the invention.

Fig. 2 is a similar view showing the parts in cranking position.

Fig. 3 is a section taken substantially on the line 3—3 of Fig. 1.

In Fig. 1 of the drawing there is illustrated a power shaft 1 on which a driving head 2 is fixedly mounted as by means of a cross pin 3. A screw shaft and pinion member 4 is slidably journaled on the power shaft 1 for longitudinal movement into and out of mesh with an engine gear 5, the meshing position of the pinion being defined by a stop sleeve 6 fixed in any suitable manner on the power shaft 1.

Driving head 2 is provided with shoulders 7 and 8 formed by milling flats 9 and 11 oppositely located on the driving head as shown in section in Fig. 3. An anchor plate 12 having a "double D" opening therein conforming to the flattened section of the driving head is seated thereon against the shoulders 7, 8 and is provided with a radial slot 13 for the reception of the outturned end 14 of a drive spring 15.

A control nut 16 is threaded on the screw shaft 4 and is provided with a radial flange 17 having a notch 18 receiving the opposite end 19 of the driving spring 15 whereby the spring forms a yielding driving connection through driving head 2 and anchor plate 12 to the control nut 16.

2

A barrel member 21 is arranged to surround the spring 15, anchor plate 12, and flange 17 of control nut 16, and has an inturned flange 22 bearing on the outer side of the end flange 17.

At its other end a thrust ring 23 seated on a reduced portion 24 of the driving head is retained in the barrel by a lock ring 25 so as to bear against the anchor plate 12 and apply an initial compressive force on the drive spring 15.

10 A thrust washer 26 is located on the power shaft 1 between the driving head 2 and screw shaft 4, serving to arrest the demeshing movement of the screw shaft, and also forming an abutment for the control nut 16 when it is pressed

15 backward by the screw-jack action of the screw shaft and control nut, thereby limiting the compression of the transmission spring 15 as shown in Fig. 2.

In order to assist in the traversal of the pinion 4 and screw shaft 4, a counterweight ring 27 is journaled on the hub 28 of the pinion and is pressed against the ends of the pinion teeth by means of a spring washer 29 which is maintained under compression by a lock ring 31. Due

25 to the frictional mounting of the counterweight 27 it also acts as a rebound check for the pinion, preventing the pinion from bounding backward toward the engine gear when it is thrown out of mesh as the engine starts.

30 Means for normally maintaining the screw shaft and pinion member 4 in idle position is provided in the form of a detent member 32 traversing the control nut 16 and bearing on the inclined shoulder 33 of the screw shaft under pressure of a spring member 34.

In operation, starting with the parts in the positions illustrated in Fig. 1, rotation of the power shaft 1 is transmitted through the driving head 2, anchor plate 12, and transmission spring

40 15 to the control nut 16. This causes traversal of the screw shaft and pinion member 4 to the right until the pinion engages the stop sleeve 6 whereupon rotation of the pinion causes rotation of the engine gear 5.

45 When the cranking load is thus applied to the transmission spring 15, it is first compressed by the backward movement of the control nut 16 due to the screw-jack action of the screw shaft and nut, and when the control nut engages the thrust washer 26, the spring 15 wraps down on the cylindrical surfaces of the control nut and driving head, which thus form an interior support for the spring.

When the engine starts, the pinion and screw shaft member 4 is returned to its idle position

with the end of the screw shaft abutting the thrust washer 26, the counterweight 27 continuing to rotate until its momentum is dissipated, the frictional torque exerted thereby holding the screw shaft and pinion in demeshed position and preventing rebounding toward the engine gear.

Although certain structure has been shown and described in detail, it will be understood that changes may be made in the precise form and arrangement of the parts without departing from the spirit of the invention.

I claim:

1. In an engine start driver, a power shaft, a driving head fixed thereon having a radial shoulder, an anchor plate with a radial slot formed therein, non-rotatably mounted on the driving head and seated against said shoulder, a screw shaft slidably journaled on the power shaft having a pinion on one end movable therewith into and out of mesh with a gear of an engine to be started, a nut threaded on the screw shaft having a flange with a radial slot formed

therein, a coiled spring surrounding the driving head and nut and having out-turned ends anchored in the slots of said anchor plate and nut flange; and a barrel surrounding the spring, retaining the ends of the spring in said slots and limiting the separation of the anchor plate and nut flange so as to maintain the spring under initial compression.

2. An engine starter drive as set forth in claim 1, including further, means independent of said nut for limiting the meshing movement of the screw shaft and pinion, whereby the scraw-jack action of the screw shaft and nut compresses said spring.

3. An engine starter drive as set forth in claim 1, including further, an eccentric weight ring journaled on the hub of the pinion, and spring means pressing the weight ring against the ends of the pinion teeth to frictionally connect the weight ring to the pinion.

JAMES J. DIGBY.
